ACOUSTICAL CEILING CONSTRUCTION

John E. Stanley, North Hollywood, Calif., assignor to
Duo-Flex Corporation, Los Angeles, Calif., a corporation

Application March 18, 1952, Serial No. 277,180

5 Claims. (Cl. 189—85)

This invention relates to ceiling constructions, more particularly acoustical ceilings that are suspended from overhead building structures, and is directed to an acoustical ceiling construction that not only affords labor savings in installation cost but also provides structural advantages as a finished ceiling.

The basic feature of the present invention is the concept that important advantages may be afforded by forming the tiles with kerfs or longitudinal slots in their edge faces into which suitable means may be inserted for supporting the tiles. One important advantage is that in such an arrangement the supporting means that engages the tile does not mask any portion of the lower face of the tile to lower the acoustical efficiency of the ceiling.

A further feature of the preferred practice of the present invention is the concept of employing transverse auxiliary tile-supporting members to span the spaces between the parallel ceiling panel members for engagement with corresponding edges of the acoustical tile. Since the ends of such auxiliary supporting members impose loads at spaced points on the parallel ceiling panels, the ceiling panel members must be efficient structural members. The proposed method of supporting the tiles by edge slots, however, makes it possible to use panels that are in the form of hollow beams of high efficiency with respect to 35 rigidity and strength.

In accord with these concepts the panels are preferably in the form of sheet metal channels having upwardly extending legs or side flanges that are offset inwardly to provide external shoulders and corresponding internal shoulders.

Since such hollow-beam panels may support loads concentrated at spaced points on their longitudinal shoulders, it is possible to support the acoustical tiles primarily if not entirely by means of the transverse auxiliary support members with no necessity for direct supporting connection between the tiles and the hollow-beam panels themselves. A feature of the invention stemming from this new method of supporting the acoustical tiles is that the tiles may merely abut the sides of the hollow-beam panels without overlap. This construction permits adjacent pairs of tiles to be pivotally moved upwardly for removal from the ceiling structure whenever it is desired to gain access to an area above the ceiling tiles.

Preferably the arrangement is such that the bottom faces of the acoustical tiles are substantially flush with the bottom faces of the hollow-beam panels so that the surface of the whole ceiling is in one plane to give the ceiling the pleasing appearance of a smooth continuous surface. The desired alignment of the bottom face of a tile with the bottom face of the adjacent hollow beam panel is attained simply by making the vertical dimension from the bottom face of the hollow beam panel to the surface of the longitudinal shoulder of the hollow beam panel substantially equal to the vertical dimension from the bottom surface of the tile to the edge slot of the tile by which the tile is supported. The transverse auxiliary support members have horizontal side flanges that both extend into the edge slots of the tiles and rest on the longitudinal shoulders of the hollow-beam panels so that the described dimensioning results in the bottom faces of the tiles is flush with the bottom faces of the hollow-beam panels.

2

Preferably the auxiliary support members are in the form of what may be termed T-splines since they have the cross-sectional configuration of an inverted T. The inverted stem of the T provides the strength and rigidity required for support of the tiles. In the preferred practice of the invention a substantially air-tight ceiling construction is achieved by also using flat splines in the form of strips to serve as spacers on the support shoulders of the hollow-beam panels between the T-splines. One longitudinal extending half of each flat spline rests on a support shoulder of a hollow-beam panel and the other half extends into the edge slot of an adjacent tile.

The various features and advantages of the invention will be apparent in the following detailed description of the preferred practice of the invention considered with the accompanying drawings. In the drawings, which are to be regarded as merely illustrative:

Figure 1 is a perspective view of a portion of an acoustical ceiling constructed in accord with the teachings of the invention,

Figure 2 is a perspective view partly in section showing how the various members of the new combination are inter-related in a ceiling construction for the support of acoustical tile,

Figure 3 is a perspective view of a preferred embodiment of the hanger clip for supporting the hollow-beam panels from the overhead runner channels,

Figure 4 is a fragmentary sectional view, the section being taken transversely of one of the splines, and

Figure 5 is a similar fragmentary sectional view taken transversely of a hollow-beam panel.

As shown in Figure 2 the principal parts of the structural combination for supporting the acoustical ceiling tiles include: a hollow-beam panel generally designated 10; a hanger member or hanger clip 11 to support the beam for an overhead runner channel 12; an auxiliary support member or spline generally designated 13; and, finally suitable flat splines 14 to serve as spacers between the T-splines 13.

The hollow-beam panel 10 is in the form of a channel member of suitable sheet metal having a web or bottom wall 18 and two upwardly extending legs or flanges 19, each of the side flanges being offset to form an external longitudinal support shoulder 20 and a corresponding internal longitudinal shoulder 21. Thus the interior of the hollow-beam panel has what may be termed the configuration of an inverted T.

Each hanger clip 11 is preferably made of suitable sheet material, such as suitably pliable sheet metal, and is cut to the general configuration of an inverted T to fit inside a hollow-beam panel 10. Thus, as best shown in Figure 3, the hanger clip is formed with two upwardly directed shoulders 25 to engage the corresponding downwardly directed interior shoulders 21 of the hollow-beam panel.

Such a sheet metal hanger clip may be adapted in any suitable manner for attachment to an overhead runner channel 12. In the preferred practice of the invention the hanger clip is adapted to be bent into permanent engagement with the runner channel by hand or by hand tools, the material of the hanger clip being suitably pliable for this purpose. In the particular construction shown, the hanger clip 11 is formed with a plurality of fingers adapted to be bent into permanent engagement with the upper and lower flanges, respectively, of the runner channel 12.

Thus, as best shown in Figure 3, the sheet metal of the hanger clip 11 is slit to form a broad central finger 26 flanked by two side fingers 27. The two side fingers 27 are bent substantially perpendicularly to extend under the bottom flange 28 of the runner channel 12 and the central finger 26 is bent to angular configuration in similar

manner, as shown in Figure 3, to extend over the top flange 29 of the runner channel. It can be seen that the vertical spacing between the two side fingers 27 and the central finger 26 of the hanger clip 11 is substantially equal to the over-all vertical dimension of the runner channel 12.

The hanger clip 11 may be readily engaged with the hollow-beam panel 10 by simply inserting the clip into the interior of the channel, the clip being turned upon its longitudinal axis to make such insertion possible and then being rotated to bring the two shoulders 25 of the clip into engagement with the internal shoulders 21 of the hollow-beam panel. The hanger clip may then be shifted longitudinally along the interior of the hollow-beam panel to a position flat against the back of the runner channel 12 and then, by means of hand tools, the two side fingers 27 may be bent over into permanent engagement with the bottom flange 28 of the runner channel as best shown in Figure 2, and in similar manner the central finger 26 may be bent over into engagement with the top flange 29 of the runner channel.

The transverse support members or T-splines 13 may be fabricated in a simple manner from suitable strips of sheet metal by folding each strip of metal on itself to form a double-thickness vertical web 33 and by bending the two thicknesses of metal respectively to form horizontal bottom flanges 34.

The flat splines 14 are substantially of the same thickness as the bottom flanges 34 of the splines 13 and preferably are of a width on the order of twice the width of a support shoulder 20 of a hollow-beam panel 10. Such flat splines may be made of any suitable material. Fibrous sheet material may be employed. The splines are not depended upon to carry weight and therefore are not stressed to any significant degree.

The acoustical tiles, generally designated by numerals 35, are of more or less conventional construction but, for the purpose of the present invention, each tile is formed with a longitudinal kerf or slot 38 on each of two opposite edge faces for engagement with the flanges 34 of the T-splines as best shown in Figure 4. In the present preferred practice of the invention, the other two parallel edge faces of the acoustical tile are also formed with a slot 38 for engagement with flat splines 14. Thus by preference each tile 35 has a continuous slot 38 around its four edge faces.

The manner in which the described structural elements may be assembled for the installation of an acoustical ceiling may be readily understood from the foregoing description. By way of example, Figure 1 shows a finished ceiling incorporating the structural members of the present invention.

In preparation for the installation of the ceiling in Figure 1, lengths of conventional edge moulds 40 are installed on the four walls of the room at the desired ceiling level. The edge moulds 40 are of well known construction being in the form of angle members having vertical flanges 41 that are attached to the room walls by suitable screws and having horizontal flanges 42 that extend around the margins of the finished ceiling.

After the edge moulds 40 are installed, the hollow-beam panels 10 are installed by using hanger clips 11 to suspend the hollow-beam panels from the overhead runner channels 12 in the manner heretofore described. The ends of the hollow-beam panels 10 at the opposite walls of the room rest on the horizontal flanges 42 of the corresponding edge moulds 40. The spacing between two hollow-beam panels 10 conforms to the width of one row of the acoustical tiles 35. In the particular installation shown in Figure 1, the individual tiles 35 are of rectangular configuration being dimensioned 12" x 24". The individual tiles 35 are formed with tapered grooves 44 on their lower faces to divide their lower faces into two equal squares. Thus, as viewed from below, each tile 35 has the appear-

ance of two separate square tiles. The hollow-beam panels 10 are spaced 24 inches apart measured edge-to-edge to accommodate the long dimensions of the rectangular tiles.

For economical use of material it is desirable that some means be provided to splice lengths of the hollow-beam panels 10 together. A feature of the invention in this respect is the use of what may be termed splicing sleeves that are dimensioned and adapted to telescope into the abutting ends of two lengths of the hollow-beam panel to splice the two lengths together. A further feature of the invention is the concept of making such splicing sleeves out of scrap lengths of the hollow-beam panel 10 by, in effect, crimping the scrap lengths to contract their cross-sectional dimensions sufficiently for snug fit of the splicing sleeves inside the ends of hollow-beam panels.

Figure 5 shows in cross-section a splicing sleeve, generally designated 45, that is crimped or indented longitudinally on each side as indicated at 46 for contraction of the cross-sectional dimensions to make the required fit. The crimping operation may be performed on suitable dies for accurate and uniform results. When manufactured in this manner for relatively close fit, a splicing sleeve as short as 8 inches in length is adequate for the purpose, especially so because the hanger clips 11 afford such efficient support for the hollow-beam panels that little or no stress is imposed on the splicing sleeves.

When the installation of the parallel hollow-beam panels 10 has been completed, the T-splines 13 are placed in parallel positions spanning the spaces between the hollow-beam panels 10, the two horizontal bottom flanges 34 of the T-splines resting at each end on the corresponding horizontal support shoulders 20 of the hollow-beam panels. It is a simple matter to insert the individual flat splines 14 into the kerfs or slots 38 at the opposite ends of an acoustical tile 35 and to tilt the tile upward through the space between two of the hollow-beam panels 10 and then lower the tile to a horizontal position. The two kerfs or slots 38 of the longer edge faces of the tile are then engaged with the corresponding bottom flanges 34 of the T-splines 13 for permanent support, the acoustical tile with the flat splines 14 resting on the support shoulders 20 of the hollow-beam panels. Approximately one longitudinal half of each flat spline 14 rests on the support shoulder 20, the other longitudinal half extending into the kerf or slot 38 of the shorter edge face of the acoustical tile. Since the kerfs or slots 38 in the edge faces of the tile are a given distance above the lower faces of the tiles and since the support shoulders 20 of the hollow-beam panels 10 are substantially the same distance above the bottom faces 18 of the panels, the bottom faces of the acoustical tiles are substantially at the same level as the bottom faces of the hollow-beam panels. Thus the surface of the finished ceiling lies substantially in one plane.

It is important to note that the full area of the individual acoustical tiles are completely exposed so that the maximum acoustical effect of the individual tiles is realized. The only exception in this respect is that the longitudinal edges of the tiles bordering on two of the side walls of the room rest on the corresponding edge moulds 40 and are thereby masked to minor extent.

It may readily be appreciated that the resulting ceiling construction is structurally efficient. The individual acoustical tiles are incorporated in a sturdy and stable mechanical structure in which a network of metal frame members is adequately anchored to the building itself. The addition of the flat splines 14 to serve as spacers between the T-splines 13 makes the ceiling substantially air-tight, the ceiling being superior in this respect.

As the tiles are pendently supported between juxtaposed pairs of panels 10 by the splines 13, there is, as previously explained, no overlapping of the tiles and panels. Thus, as best shown in Figure 1, adjacent pairs of tiles, except those disposed directly beneath the channels 12 may be pivoted upwardly in opposite directions to

disengage the adjoining edges of the tiles from the supporting spline whereupon the tiles may be removed from the ceiling. This feature of the present invention is important, as it permits easy access to areas above the ceiling tiles.

My description in specific detail of the presently preferred embodiment of the invention will suggest to those skilled in the art various changes, substitutions and other departures from my disclosure that properly lie within the spirit and scope of the appended claims.

I claim:

1. In a ceiling construction of the type described, comprising: a plurality of elongated main support panels, each having a planar lower face and presenting an upwardly facing continuous shoulder on each of its longitudinal sides and at a given distance from said planar lower face; means for securing said panels in spaced parallel relationship to the framework of a building; rows of ceiling surface forming tiles disposed between said panels, said tiles having a length substantially equal to the distance between the opposed outermost vertical surfaces of any pair of said panels; auxiliary support members intermediate each adjacent pair of tiles in a row, said auxiliary support members having their opposite end portions seated on the shoulders of adjacent panels; means carried by each auxiliary support member for engaging in kerfs formed in contiguous faces of adjacent tiles at said given distance from the lower faces of said tiles whereby said tiles are supported with the lower faces thereof substantially flush with the planar faces of said panels and the opposite end faces in facewise engagement with the adjacent side faces of juxtaposed panels; and a flat spline anchored in each of said end faces of the tiles and having one longitudinal half resting on the adjacent panel shoulder for sealing the space between the end faces of said tiles and the side faces of said panels.

2. In a demountable ceiling suspension construction of the type described, comprising: a plurality of hollow elongated main support panels, each having a planar lower face with planar side faces normal thereto and presenting an upwardly facing continuous shoulder on each of its longitudinal sides and at a given distance from said planar lower face; each panel including an extension directed upwardly from the inner edge of each shoulder to provide surfaces inset from said side faces; means for securing said panels in spaced parallel relationship to the framework of a building; rows of ceiling surface-forming tiles disposed between said panels, said tiles having planar end faces and each being of a length equal to the distance between adjacent side faces of juxtaposed panels whereby the planar end faces of said tiles facewisely engage with adjacent side faces of juxtaposed panels; auxiliary support members intermediate each adjacent pair of tiles of a row, said auxiliary support members having a length greater than the distance between a side face of one panel and the inset surface of the juxtaposed panel and having their opposite end portions seated on the shoulders of juxtaposed panels; and oppositely projecting flange means carried by each auxiliary support member engaging in kerfs formed in contiguous faces of adjacent tiles at such a distance from the lower faces of said tiles that said tiles are pendants supported solely by said auxiliary support means with the lower faces of said tiles substantially flush with the planar faces of said panels.

3. In a demountable ceiling suspension construction of the type described, comprising: a plurality of hollow elongate main support panels, each having a planar lower face with planar side faces normal thereto and presenting an upwardly facing continuous shoulder on each of its longitudinal sides and at a given distance from said planar lower face; means for securing said panels in spaced parallel relationship to the framework of a building; rows of ceiling surface-forming tiles disposed between said panels and spanning the distance between adjacent side faces of juxtaposed panels, said tiles having planar end

faces facewisely engaged with said adjacent side faces of juxtaposed panels; auxiliary support members intermediate each adjacent pair of tiles of a row and having their opposite end portions seated on the shoulder of juxtaposed panels whereby said auxiliary support members are supported by said panels; means forming a part of each panel and cooperative with said auxiliary support members for holding said auxiliary support members against a longitudinal movement sufficient to disengage an opposite end of said auxiliary support member from the shoulder engaged thereby; and means carried by each auxiliary support member engaging in kerfs formed in contiguous faces of adjacent tiles at such a distance from the lower faces of said tiles that said tiles are pendants supported between juxtaposed main support panels solely by said auxiliary support members with the lower faces of said tiles substantially flush with the planar lower faces of said panels.

4. In a ceiling construction as recited in claim 3 wherein said means forming a part of each panel includes a flange extending upwardly from the inner edge of each shoulder to cooperate with said auxiliary support members for holding said auxiliary support members against a longitudinal movement sufficient to disengage an opposite end of said auxiliary support member from the shoulder engaged thereby, said upwardly extending flanges in combination with said planar side faces providing weight supporting structural rigidity for said panels.

5. A ceiling construction in a building structure, comprising: a plurality of rectangular ceiling tiles arranged in rows, each having a kerf on at least two side edges parallel to its bottom face and at a given distance from its bottom face; a plurality of spaced parallel ceiling panels positioned as spacers between rows of said tiles in edge-to-edge abutment with the tiles, each of said panels having a bottom face substantially flush with the bottom faces of the tiles, each of said panels having an upwardly facing longitudinal shoulder on each of its two longitudinal sides at substantially said given distance from said bottom face of the panel; hanger members extending from above to said panels and supporting the panels from the building structure; auxiliary support members perpendicular to said panels spanning the spaces between the panels and extending between each pair of successive rows of the tiles, said auxiliary support members having their opposite ends resting on said shoulders of the panels and having the configuration of an inverted T providing side flanges extending into the kerfs of the tiles as sole supports for the tiles, and flat splines perpendicular to said auxiliary support members and spanning the spaces therebetween, each of said splines having approximately one longitudinal half resting on one of said panel shoulders and the other approximate longitudinal half extending into a kerf formed in the adjacent tile.
